UNITED STATES PATENT OFFICE.

EMMA F. HARMON, OF CONNEAUT, OHIO.

DESIGN FOR A GARMENT-MEASURE.

Specification forming part of Design No. 5,138, dated July 25, 1871.

To all whom it may concern:

Be it known that I, Mrs. EMMA F. HARMON, of Conneaut, in the county of Ashtabula and State of Ohio, have invented a new and Improved Design for Garment-Measure; and I do hereby declare that the following is a full, clear, and exact description thereof, which will enable others to make and use the same, reference being had to the accompanying drawing forming part of this specification.

Figure 1 represents a face view of my new pattern-gauger. Fig. 2 is a face view of an attachment thereto.

Similar letters of reference indicate corresponding parts.

This invention relates to a new form of pattern-gauger for laying out and measuring coats, shirts,

jackets, and similar garments. The design of the pattern A, shown in Fig. 1, is intended for measuring the arms and laying out the proper curves for the same. Its shape is similar to a crook, and its edges have a graduated scale marked thereon for obtaining the several measurements. The pattern B shown in Fig. 2 is used in combination with the pattern A to continue the lines marked by the latter. It is of peculiar outline, as shown. These patterns are cut out of or marked upon paper, pasteboard, or other suitable material.

I claim as my invention—

The design for garment-measure, as shown.

Witnesses: MRS. E. F. HARMON.
